US00D881832S

(12) **United States Design Patent** (10) Patent No.: **US D881,832 S**
(45) Date of Patent: **** Apr. 21, 2020**

(54) **AUDIO RECEIVER TRANSMITTER**

(71) Applicant: **Qinbing Zhang**, Shanghai (CN)

(72) Inventor: **Qinbing Zhang**, Shanghai (CN)

(73) Assignee: **Shanghai Xinxie Industrial Co., Ltd**,
Shanghai (CN)

(**) Term: **15 Years**

(21) Appl. No.: **29/680,882**

(22) Filed: **Feb. 21, 2019**

(51) LOC (12) Cl. **14-03**

(52) U.S. Cl.

USPC **D14/155**

(57) **CLAIM**

The ornamental design for an audio receiver transmitter, as shown and described.

DESCRIPTION

FIG. 1 is a top, front perspective view of the audio receiver transmitter showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is a front perspective view thereof, showing the audio receiver transmitter in alternate position.
